UNITED STATES PATENT OFFICE

2,450,088

OPEN-FRONT REFRIGERATED DISPLAY
CABINET

Elden O. Henderson, Oklahoma City, Okla., assignor to E. O. Henderson & Sons, Oklahoma City, Okla., a partnership

Application April 8, 1947, Serial No. 740,058

4 Claims. (Cl. 62—89.5)

1

This invention relates to a refrigerating apparatus embodying a cabinet which is constructed to provide a walk-in storage section and an open-front or refrigerated display section in communication with the storage section, to the end that a single motor driven refrigerating unit may be used in supplying the cooling medium for both the storage section and display section.

An important object of the invention is to construct the cabinet of the device in such a way that a cooled area will be set up within the display section, to prevent the warm air of the room in which the cabinet is positioned, being drawn into the display section and passed into the storage section.

With the foregoing and other objects in view, which will appear as the description proceeds, the invention consists of certain novel details of construction and combinations of parts, herein-after more fully described and pointed out in the claims, it being understood that changes may be made in the construction and arrangement of parts without departing from the spirit of the invention as claimed.

Referring to the drawings.

Figure 1 is a perspective view of a refrigerating cabinet, constructed in accordance with the invention.

Figure 2 is a vertical sectional view through the cabinet of the apparatus.

Figure 3 is a sectional view taken on line 3—3 of Figure 2.

Figure 4 is a vertical sectional view through a modified form of the invention.

Referring to the drawing in detail, the device comprises an insulated cabinet indicated generally by the reference character 5, the cabinet having a door 6 in one end thereof to permit an attendant to walk into the cabinet or storage space of the cabinet.

The reference character 7 indicates the lower section of the front wall of the cabinet, which extends to a point slightly half of the distance between the floor and top of the cabinet, as clearly shown by Figure 1 of the drawings.

Extending upwardly from the upper edge of the front wall 7, is a transparent extension section 8 through which the articles supported within the display section of the cabinet, may be viewed.

The reference character 9 indicates the upper section of the front wall of the cabinet, the upper section extending downwardly an appreciable distance from the top of the cabinet, where it is supplied with openings to accommodate trans-

2

parent slides having certain indicating characters thereon indicating the type of merchandise contained in the display section of the device.

The reference character 10 indicates a perforated support or shelf which is supported by means of the legs 11 and cross-bar 12 connecting the legs 11 at their upper ends.

The reference character 13 indicates an inwardly and downwardly inclined wall that extends to a point below a line drawn horizontally through the cabinet, touching the upper edge of the transparent extension section 8, providing a compartment 14 with an inclined upper wall.

Hingedly connected to the lower edge of the wall 13, is a perforated wall 15 which establishes communication between the compartment 14 and storage compartment 16 directly behind the compartment 14. The perforated wall 15 may be swung inwardly so that the shelf 10 may be manually charged with merchandise by a person within the cabinet.

The mirror indicated at 17 is positioned on the front surface of the wall 13, and reflects the fruit or vegetables which are positioned on the perforated support or shelf 10.

Due to the location of the inclined wall 13, a triangular niche or space 24 is formed within the upper front portion of the cabinet 5. This space lies below the cabinet roof above and adjacent the inside surface of the wall 13.

Rigidly disposed within the triangular space 24, and located adjacent the transverse center thereof, there is provided a cooling element 18 which includes a conventional refrigerant expansion coil, not shown. As a means for mechanically causing a circulation of the air contained in the cabinet, and for continuously and repeatedly passing such air through the cooling element 18, there is provided a suitable electrically driven fan 19. The fan 19 is adapted to create air circulation within the cabinet in the directions indicated by the arrows in Figure 2.

It is pointed out that due to the fact that the fan 19 creates a suction in the upper front corner of the space 24, and exhausts the air as it is drawn from this corner through the cooling element and toward the rear of the cabinet along its roof, the circulation is cyclonic in nature. By the time this circulating air passes between the legs 11 and upwardly through the perforations in the shelf 10, it has reached its lowest velocity. The air at this point has traveled the greatest distance from the cooling element 18, and is therefore at a higher temperature than it is at any other point in the cabinet. The compara-

tively warm air therefore has a natural tendency to rise.

The fan 19 is so located with relation to the inclined wall 13, that the warmer slow moving air at lower end of the wall 13, is sucked upwardly by the fan along the inside surface of the wall.

Due to the fact that walls 7 and 8 overlap vertically or extend above the lower portion of the inclined wall 13, there is provided an air pocket above the shelf 10 which creates a substantially horizontal stratum of dead air. This stratum lies between the adjacent faces of the overlapping portions of the walls (7-8) and the wall 13.

Since this stratum of air is much colder than the outside warm air thereabove, the cold stratum presents a barrier which prevents the downward movement of such outside warm air and therefore prevents its entry into the cabinet through the perforated wall 15.

Directly above the mirror 17, are slides 20 on which may be displayed the merchandise price and descriptive menu.

The apparatus, shown in the drawings and described hereinabove, constitutes a forced air circulation system. It is pointed out, however, that by deleting the fan 19 from the apparatus, the device would be converted in the gravity system which is capable of functioning to cool merchandise placed upon the shelf 10. Such an embodiment would not be as efficient as the forced circulation system, but the air would circulate by gravity in substantially the path indicated by the arrows in Figure 2, although such circulation would take place at considerably less speed.

Suitable hooks such as indicated at 21 may be provided within the cabinet, on which articles may be hung while stored.

It will also be noted that electric lamps 22, are provided in proximity to the transparent slides in the section 9 of the front wall illuminating the slides.

The principal object of the modified form of the invention as shown by Figure 4 is to increase the display shelf capacity of the device without materially increasing the cost of the apparatus, and without a substantial decrease in the efficiency of the air cooling element 18 and its associated air circulating unit 19.

With this object in mind, the lower portion of the inclined wall section 13' is provided with spaced openings 25 and 26 which extend horizontally for substantially the entire length of the section 13'. Each of the openings has its inner end closed by a door 27 hingedly connected along its upper edge to the upper wall of the respective openings.

A horizontal forwardly projecting shelf 27' of imperforate sheet material is rigidly positioned on the lower wall of the opening 25, with its front edge supported by a horizontal beam 28 attached to the end walls of the cabinet 5. The beam 28 also supports the lower edge an upwardly extending glass panel or sheet 29 which extends above the level of the upper wall of the opening 25. The shelf 27' and panel 29 preferably extend the entire length of the cabinet.

The lower wall of the upper opening 26 has a similarly mounted horizontal forwardly projecting imperforate shelf 30 which is supported along its front edge by a beam 31. The beam 31 supports an upwardly projecting glass panel 32 similar to the above described panel 29, and

which extends upwardly beyond the level of the upper wall of the opening 26. The opening 26 has a hinged perforated door 33 similar to the door 27 in the opening 25.

In this embodiment of the invention a portion of the cold air which during its circulation and return to the fan 19', travels along the inside surface of the wall section 13', passes through the cabinet along the upper surface of the shelf 27'. This circulating cold air fills the space above the shelf to a vertical point, approximately even with the upper wall of the opening 25. Air at outside atmospheric temperature occupies the space lying above said shelf 27' and below the upper shelf 30, and this warmer outside air is prevented from entering the cabinet or open refrigerated space lying above shelf 27', the cold stratum air acting as a barrier to outside infiltration.

The air traveling upwardly along the inside surface of the wall section 13' creates a syphoning suction beneath the upper wall of openings 25 and 26, and this suction creates a circulation of the cold air above the shelves substantially as indicated by the arrows in Figure 4. The result is that any merchandise placed upon the shelves will be refrigerated. The bottoms of the shelves 27' and 30 are provided with a heat insulating layer 34.

The same circulation of cold air is provided in a similar manner above the shelf 30' as indicated by the arrows directly thereabove.

Another object of the present embodiment is to provide means whereby the cabinet may be converted into a freezing unit instead of being merely a cooling apparatus.

With this end in view, a vertical depending curtain, wall or partition 35 is provided at a point substantially even with the rear open face 40 of the cooling element 18'. The wall 35 extends entirely from end to end of the cabinet, and its upper edge terminates a slight distance below the cabinet roof. The lower edge of the wall 35 terminates approximately even with the upper edge of the opening 26, but does not meet the inclined front wall 13. The wall 35 is cut out to fit snugly around the cooling element 18'.

With the wall 35 in place as shown, it is possible to freeze merchandise within the cabinet 5 as well as upon all of the shelves 10, 27' and 30, by merely increasing the flow of refrigerant to the cooling unit and also speeding up the fan. A portion of the circulating air returns to the triangular compartment 24 over the top of the wall 35, as indicated by some of the arrows in Figure 4.

It might be further stated that in the form of the invention as shown by Figure 4 of the drawings, a transparent wall 8' is provided along the front edge of the perforated shelf 30' and extends upwardly an appreciable distance.

At the rear of the compartment is a perforated hinged closure 9' which may be swung upwardly to permit articles of food to be positioned on the shelf 30' from a point within the cabinet.

From the foregoing, it will be seen that I have provided a cabinet including a walk-in storage space at the rear thereof, and a front section for containing the articles to be sold, the articles being on display to be picked up by persons in carrying out the self-service sales system.

What is claimed is:

1. A refrigerating apparatus comprising a cabinet, an inwardly and downwardly inclined wall extending from the front edge of the top of the

cabinet, dividing the cabinet into a storage compartment and a forward display compartment, a perforated shelf supported within the display compartment and on which articles are supported, the space below the shelf being open to induce circulation, a perforated wall connected with the inwardly and downwardly inclined wall, and engaging the shelf at the rear edge thereof, a refrigerating unit mounted within the storage compartment within the space between the upper end of the inclined wall and top of the cabinet, and said refrigerating unit adapted to create a circulation of cool air through the shelf, perforated wall and storage compartment.

2. A refrigerating apparatus, including a cabinet having in combination, a vertically disposed lower front wall section extending upwardly from the cabinet floor and terminating below the cabinet roof, an upper depending front wall section having its upper edge connected to the cabinet roof above said lower section, said upper section being inclined downwardly and inwardly to a point lying below and spaced inwardly from the upper edge of said lower section, plural perforated horizontal shelves extending inwardly from

15

25

the inner surface of said lower section to a point lying below and spaced vertically from the lower edge of said upper section, and means in said cabinet for cooling and circulating the air therein.

3. Structure as specified in claim 2, in which said air-cooling and circulating means includes a refrigerating element, and a fan for driving air through said element.

4. Structure as specified in claim 2, in which 10 said means includes a refrigerating element disposed in the upper portion of said cabinet, and a fan for withdrawing air from the space within said cabinet lying above said upper wall section, and for exhausting said air through said element toward the rear of the cabinet.
